James W. McLaughlin, of Cincinnati, Ohio.

Letters Patent No. 2095, Dated June 13, 1865.

Design for a Monument.

The schedule referred to in these Letters Patent and making part of the same.

To all whom it may concern:

Be it known that I, James W. McLaughlin, of Cincinnati, in the County of Hamilton and State of Ohio, have invented an ornamental design for a monument, and I do declare the same is fully and correctly represented in the accompanying drawings which are hereby made a part of this specification.

I claim as new and desire to have secured to me by Letters Patent:

The ornamental design for a monument represented in the accompanying drawings,

Witnessing of which invention I hereunto set my hand.

Witnesses:

Geo. W. Knight,

James McLaughlin,

Gas. W. McLaughlin,
